(57) **CLAIM**

I claim, the ornamental design for a 3D printer, as shown and
described herein.

DESCRIPTION

FIG. 1 is a front top right perspective view of the 3D printer,
showing my new design;

FIG. 2 is a front bottom left perspective view thereof;

FIG. 3 is a rear top left perspective view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a right side elevation view thereof; and,

FIG. 9 is a left side elevation view thereof.

The dashed lines showing borders of air-vents illustrated in
FIGS. 1-3, 6, 8, and 9 and the control buttons illustrated in
FIGS. 1, 2, 4, and 6 as well as the 3D Printer floor illustrated
in FIG. 7 are included for illustrating environmental structure
and form no part of the claimed design.

The surface shading vertical and horizontal lines on the
claimed portion illustrated in FIGS. 1-9 are provided only to
indicate the character and/or any contour or curvature of the
surfaces. They do not indicate color, texture, markings that
actually exist thereon, indicia, graphic representations, sur-
face treatment, or any other ornamentation applied to the
article.
